[57] CLAIM

The ornamental design for snow globe/spray fragrance bottle, as shown and described.

DESCRIPTION

FIG. 1 is a top, front perspective view of the snow globe/spray fragrance bottle of my new design of which includes both a snow globe and a fragrance spray bottle; FIG. 2 is a top plan view thereof;

FIG. 3 is a right side elevation view thereof shown in exploded view with the cap removed; the left side elevation view is the same as the right side elevation view;

FIG. 4 is a rear elevation view thereof;

FIG. 5 is a bottom plan view thereof;

FIG. 6 is a top, front perspective view of a second embodiment of the snow globe/spray fragrance bottle, the sole difference being in the removal of the fragrance bottle;

FIG. 7 is a top plan view of FIG. 6;

FIG. 8 is a right side elevation view of FIG. 6; the left side elevation is the same as the right side elevation view; and, FIG. 9 is a rear elevation view thereof; the bottom plan view not shown is the same as FIG. 5.
